UNITED STATES PATENT OFFICE.

JAY MILLER SCOTT, OF WINNIPEG, MANITOBA, CANADA.

AUTOMATIC DERAILMENT BRAKE ATTACHMENT.

1,412,141.

Specification of Letters Patent. Patented Apr. 11, 1922.

Application filed July 12, 1921. Serial No. 484,251.

To all whom it may concern:

Be it known that I, JAY MILLER SCOTT, a subject of the King of Great Britain, and a resident of the city of Winnipeg, in the 5 province of Manitoba, Canada, have invented certain new and useful Improvements in Automatic Derailment Brake Attachments, of which the following is the specification.

The invention relates to improvements in 10 automatic derailment brake attachments and an object of the invention is to provide a safety attachment for train coaches or cars, which upon the car or coach becoming derailed or parts of the trucks breaking or 15 burning out, will automatically operate to set the air brakes and thereby bring the train to a stop and avoid damaging accidents.

A further object is to construct the appliance so that it can be easily and quickly attached to standard types of cars and coaches 20 and which is arranged so that it is entirely positive and reliable in its action.

A still further object of the invention is to construct the appliance so that it will accommodate existing curvatures of the track 25 without affecting the air brake system and a still further object is to arrange the appliance in a simple, durable and comparatively inexpensive manner.

With the above more important objects in 30 view the invention consists essentially in the arrangement and construction of parts hereinafter more particularly described and later pointed out in the appended claims, 35 reference being had to the accompanying drawings in which:—

Fig. 1 is a side view of part of a passenger coach showing my invention attached thereto.

Fig. 2 is a plan view of the working parts 40 of the invention as they appear associated with the train equipment, the coach body being removed.

Fig. 3 is a sectional view at 3—3' Fig. 1 45 through the car body and looking towards the attachment which is shown in front elevation.

Fig. 4 is a longitudinal sectional view through the parts at 4—4' Fig. 2.

Fig. 5 is an enlarged detailed side view 50 of the valve and valve lever.

Fig. 6 is a vertical sectional view through the valve.

In the drawings like characters of reference indicate corresponding parts in the several figures.

The passenger coach 1 is carried in the usual manner by trucks, one of which is indicated at 2, the truck presenting the customary car wheels 3, the journal boxes 4 and the wheels being mounted in the ordinary manner between the pedestal legs 5 and 6 of the pedestal 7. The arch bars 8 are of the usual form and the truck is centrally pivoted to the car body in the usual manner to accommodate the existing curves of the railroad track.

I have not considered it necessary to detail the latter pivoted arrangement of the trucks as it is well known and one familiar 70 with car equipment knows perfectly well that the trucks have to swing to accommodate track curvatures. The pivot pin of the truck is indicated at 2'.

The wheels ride on the usual track rails 9 75 which are supported by the ties 10. At the present time passenger coaches and freight cars are for the greater part equipped with air brake systems which, upon the air pressure being reduced in the train brake pipe, 80 operate to apply the brakes and stop the car.

I have not considered it necessary to enter 85 into a detailed description of the air brake equipment, only showing those parts which are more immediately associated with my invention. These latter parts are as follows:—

The train brake pipe 11, the triple valve 12, the air reservoir 13, the cylinder 14, the 90 push rod 15, the cylinder 16, the floating lever 17 and the brake rods 18 and 19 and 20.

The pipe line passes from coach to coach throughout the length of the train and the triple valve is connected by a pipe 20 to the 95 train brake pipe and the arrangement is such that a reduction of pressure of the air in the train brake pipe acts to actuate the push rod and by so doing effect a movement in the brake rods 18 and 19 which will apply 100 the brakes (not shown) to the wheels.

In equipping a coach having the foregoing equipment or similar equipment with my invention I provide the parts now described.

To the truck I attach a longitudinally extending centrally positioned jointed controlling arm 21 which forms the operating connection between the truck and the release or safety valve 22 associated with the 110 train pipe line.

The controlling arm comprises in the pres-

ent instance three sections, a stationary section 23 permanently secured in any suitable manner to the truck frame, an intermediate vertically swingable section 24 pivotally attached by a horizontal pivot pin 25 to the extending end of the stationary section and a laterally or horizontally swingable end section 26 pivotally secured by a vertical pivot pin 27 to the end of the intermediate section.

Here it will be observed that one end of the intermediate section is cut at an angle and underlies the overhanging angularly cut end 23' of the stationary section, such arrangement preventing the right hand end of the intermediate section from swinging down below the horizontal position but permitting it to swing freely upwardly.

The extending or free end of the section 26 is utilized to operate the safety valve 22 and to this end is provided with an extending pin 28 which is received within a vertically disposed slot 29 provided in the valve lever 30 associated with the valve 22. The valve 22 is connected by the pipe 31 to the pipe 20 so that it is in direct communication with the train pipe line.

The valve opening 32 is such that when the lever is in say the closed position the pipe 31 is closed to atmosphere. This closed position of the valve and lever is shown in the drawings and obviously if the valve lever be swung upwardly the valve opening 32 will connect the pipe 31 with the duct 33 and thereby reduce the air pressure in the pipe line and consequently operate the brakes. A spring rod 34 is connected at one end to the inner end of the stationary section 23 of the controlling arm and at the other end pivotally to the intermediate section 24 of the arm, this spring rod having a natural tendency to pull down the right hand end of the central arm section so that it normally remains in the horizontal position.

The section 26 of the arm passes directly over a stationary horizontally disposed transversely extending bracket 35 having the ends secured to the car body and the bracket is arranged so that the arm section 26 rides the bracket in its normal horizontal position. Here it will be observed that the arm 21 normally extends horizontally, riding the bracket, and with the pin approximately midway in the slot 29 and the valve closed.

In order to fully understand the attachment, I will now describe its operation, considering the release valve normally closed and the parts in the position as shown in the drawings.

The swinging of the truck in making track curves is accommodated by the vertical pin 27 which permits the beam to swing laterally without withdrawing the pin from the slot 29 and without actuating the valve in any way. The slight up and down movement of

the front and back ends of the truck in riding the tracks is accommodated by the slot 29 which allows the pin a limited travel without actuating the release valve. Accordingly under normal conditions the valve 70 remains inert although the controlling arm is moving a limited extent.

Should the right hand wheels of the truck leave the track, this will produce an up-swinging of the extending end of the controlling arm as the section 26 of the beam is held against dropping by the bracket 35 and it, the beam, will accordingly have to break joint at the pivot pin 25. The intensified movement of the pin 28 so produced will 80 carry the pin initially to the upper end of the slot and then the pin will turn the lever upwardly to open the valve, reduce the pressure of the air in the train pipe and set the pipes.

Should the left hand end wheels of the truck leave the rails, this will affect the turning of the valve lever and the setting of the brakes as the beam simply swings bodily upwardly. Should a journal burn out or an arch bar break the wheel axle 36 will remain in the same position as the wheels are riding the track but the truck and car body will lower and the relative movement so produced, will cause the spring rod 34 to strike 90 the axle which will effect an up-swinging movement in the right hand end of the spring rod and the consequent up-swinging of the extending end of the controlling arm and the setting of the brakes through the 100 valve.

From the above it will be apparent that I have provided an extremely simple, yet effective, attachment for automatically setting the brakes should an irregularity occur and 105 that the device acts under all irregular conditions in normal practice.

Whilst I have shown the device as associated with one truck, still it will be understood that the attachment will be supplied 110 on all trucks and will operate in the event of any truck leaving the track or other irregularities occurring as herein before described.

Whilst I have entered into a detailed description of the various parts it will be readily understood that these could be modified without in the least departing from the spirit of the invention as set forth in the appended claims.

What I claim as my invention is:—

1. The combination with a car truck and the air brake pipe thereof, of a release valve connected to the brake pipe and a jointed sectional arm having one end permanently 125 secured to the truck, an intermediate vertically swingable section pivotally secured to the former section and a laterally swingable section pivotally secured to the intermediate section and the extending end of the 130

laterally swingable section engaging the valve.

2. The combination with a car truck and the air brake pipe thereof, of a release valve 5 attached to the brake pipe and provided with an extending forked lever and a controlling arm attached to the truck and extending towards the lever, said arm comprising a stationary section permanently 10 secured to the truck, an intermediate section pivotally attached to the latter section for vertical swinging movement and limited in its downward swing and a laterally swingable end section pivotally attached to 15 the intermediate section and having the free end thereof provided with an extending pin entered between the forks of the lever.

3. The combination with a car truck and 20 the air brake pipe thereof, of a release valve connected to the brake pipe and provided with a valve operating controlling lever presenting vertically disposed downwardly extending forks and a controlling arm carried by the truck and extending to the valve lever and comprising a stationary section secured permanently to the truck, a vertically swingable intermediate section pivotally attached to the latter section and having a limited downward swing and a laterally swingable end section pivotally attached to the intermediate section and having the free end thereof provided with a pin entered between the forks of the valve 35 lever.

4. The combination with a car truck and the air brake pipe thereof, of a release valve 40 connected to the brake pipe and provided with a valve operating controlling lever presenting vertically disposed downwardly extending forks, a controlling arm carried by the truck and extending to the valve

lever and comprising a stationary section secured permanently to the truck, a vertically swinging intermediate section pivotally attached to the latter section and having a limited downward swing and a laterally swingable end section pivotally attached to the intermediate section and having the free end thereof provided with a pin entered between the forks of the valve lever and a horizontally disposed stationary transversely extending bracket passing beneath and normally engaging the laterally swingable end section of the arm. 45 50 55

5. The combination with a car truck and the air brake pipe thereof, of a release valve connected to the brake pipe and provided with a valve operating controlling lever presenting vertically disposed downwardly 60 extending forks, a controlling arm carried by the truck and extending to the valve lever and comprising a stationary section secured permanently to the truck, a vertically swingable intermediate section pivotally attached to the latter section and having a limited downward swing and a laterally swingable end section pivotally attached to the intermediate section and having the free end thereof provided with a pin entered between the forks of the valve lever, a horizontally disposed stationary transversely extending bracket passing beneath and normally engaging the laterally swingable end section of the arm and a spring rod 65 70 75 attached to the intermediate section and the stationary section of the beam and overlying the adjacent wheel axle.

Signed at Winnipeg, this 26th day of May, 1921.

JAY MILLER SCOTT.

In the presence of—

GERALD S. ROXBURGH,
K. B. WAKEFIELD.
